COMBINED GAME PADDLE AND TETHERED BALL OR SIMILAR ARTICLE

Lawrence Jonesi, Chicago, Ill.

Application March 5, 1954, Serial No. 29,359

Term of patent 14 years

(Cl. D34—5)

To all whom it may concern:

Be it known that I, Lawrence Jonesi, a citizen of the United States, residing at Chicago, in the county of Cook and State of Illinois, have invented a new, original, and ornamental Design for a Combined Game Paddle and Tethered Ball or Similar Article, of which the following is a specification, reference being had to the accompanying drawing, forming a part thereof.

The single figure is a plan view of a combined game paddle and tethered ball or similar article, showing my new design.

The paddle is of conventional thickness, and the appearance of the back thereof, not shown, is plain or conventional.

I claim:

The ornamental design for a combined game paddle and tethered ball or similar article, as shown and described.
